UNITED STATES PATENT OFFICE.

WILLIAM A. WEBSTER, OF GALESBURG, ILLINOIS.

BALER.

1,351,452.

Specification of Letters Patent. Patented Aug. 31, 1920.

Application filed July 26, 1916. Serial No. 111,342.

To all whom it may concern:

Be it known that I, WILLIAM A. WEBSTER, a citizen of the United States, and a resident of Galesburg, county of Knox, and State of Illinois, have invented certain new and useful Improvements in Balers, of which the following is a specification.

My invention relates to improvements in balers especially adapted for use in baling paper, and has for its object the provision of an improved construction of this character by means of which paper or similar material may be readily and quickly baled.

The invention consists in the combinations and arrangements of parts hereinafter described and claimed.

The invention will be best understood by reference to the accompanying drawings forming a part of this specification, and in which,

Figure 1 is a vertical section of a baler embodying my invention, said section being taken substantially on line 1—1 of Fig. 3,

Fig. 2 a side view of the baler shown in use as baling the paper in a sack or bag,

Fig. 3—a top plan view of the baler.

Fig. 4—a horizontal section taken on line 4—4 of Fig. 1, and

Fig. 5—a perspective view of one form of bale formed in the baler.

The preferred form of construction as illustrated in the drawings, comprises an open work container having a substantially circular bottom member 6 in the form of an open work grate or frame separable in two parts and a top ring 7 also formed in two separable parts, the corresponding parts of said ring and said bottom member being permanently connected together by means of vertical slats 8 riveted into position as indicated. One of the parts of the bottom member 6 is provided with hook members 9 adapted to detachably engage corresponding lugs 10 on the other part, the hook members 9 being slightly beveled at 9' to facilitate engagement and disengagement of said parts. Likewise the parts of the ring 7 are similarly connected together, one of said parts being provided with hooks 11 adapted to detachably engage corresponding lugs 12 on the other part, the hooks being beveled at 11' to facilitate engagements and disengagements. The top ring 7 is also provided with a groove or rabbet 13 adapted to receive the upper edge of a bag or sack 14 in the con-

tainer, a band or ring 15 being provided to detachably hold said edge in position as will be readily understood. The top ring 7 is also provided with a number of perforations 16 for the accommodation of wires when it is desired to use the device for forming bales bound by means of wires.

A supporting member is arranged to extend across the open top of the container, said supporting member consisting of two side bars 18 secured in grooves 19 in the sides of a central head 20. A compression screw 21 is threaded in the head 20 and is provided at its upper end with an operating handle 22 as indicated. A compression head 23 in the form of an open work spider is provided with a central hub 24 having a socket provided therein for the reception of the screw 21. Swinging hooks 26 are pivoted between the opposite ends of bars 18 and are adapted to engage under the ring 7 as indicated to secure the support in position on the top of the container.

Two square wire frames 27 are provided for convenience in the baling operations, one of said frames 27 being designed to be inserted in the bottom of the container and the other being designed to be positioned on top of the contents of the container. The lowermost frame 27 has four chains 28 permanently secured to the corners thereof and the uppermost frame 27 has four hooks 29 permanently secured to the corners thereof adapted to engage the chains 28 two of said hooks being somewhat longer and larger than the other hooks to facilitate engagements and disengagements with said chains.

In use, one of the frames 27 is placed in the bottom of the container and chains 28 hung over the sides of the top thereof. The paper is placed in the container until full when the same is compressed by adjusting the support across the top thereof and forcing the compression spider 23 downwardly into the container. This provides room for more paper which in turn is again compressed until the container is full or the desired height of bale is obtained. Before compressing the last instalment of the paper inserted in the container, the upper frame 27 is placed in position on top of the contents of the container and the compression head 23 positioned on top of the frame. Then the contents of the container are compressed as before and the chains engaged

with the hooks 29, the open work form of the spider permitting of such engagement. This completes the bale and the compression head and coöperating parts are removed. 5 Then the container is turned upon its side and the parts thereof detached by releasing the hooks 9 and 11 from the lugs 10 and 12 which permits of the ready removal of the finished bale. If desired the bale may be 10 formed in a sack or bag 14 which has its top closed by sewing or otherwise after the baling has been completed. Or if desired the bale may be bound by wires, the perforations 16 in the top member facilitating the 15 use thereof.

While I have illustrated and described the preferred form of construction for carrying my invention into effect, this is capable of variation and modification without 20 departing from the spirit of the invention. I, therefore, do not wish to be limited to the precise details of construction set forth, but desire to avail myself of such variations and modifications as come within the scope of 25 the appended claims.

Having described my invention what I claim as new and desire to secure by Letters Patent is:

1. A container for balers comprising an 30 open work bottom member substantially circular in form and formed in two separable parts, there being a hook and lug connection between said parts; a top substantially circular ring formed in two separable 35 parts; there being a hook and lug connection between said parts; and substantially vertical slats connecting corresponding

parts of said bottom member and said top ring, substantially as described.

2. A baler comprising a container, a support 40 detachably connected therewith and comprising a pair of bars and a head fixed between said bars, said head being grooved to receive said bars, a screw threaded through said head and extending into said 45 container and a compression head on the inner end of said screw, substantially as described.

3. A baler comprising a container consisting of upper and lower members and slats 50 connecting the same, the upper member being provided with bale tie receiving apertures, and means to compress the contents of the container, substantially as described.

4. A baler comprising a container consisting of upper and lower members and slats connecting the same, said upper member being provided with a plurality of substantially radially disposed perforations and means for compressing the contents of 60 said container, substantially as described.

5. A baler as set forth in claim 6 further characterized by an upwardly extending flange on the upper member and a clamping ring coöperating with said flange, 65 substantially as described.

In testimony whereof I have signed my name to this specification in the presence of two subscribing witnesses.

WILLIAM A. WEBSTER.
